SANDING BELT MACHINE

Herman S. Newton, Temple, Tex.

Application February 26, 1945, Serial No. 579,739

6 Claims. (Cl. 51—135)

1

This invention relates to sanding machines and more particularly to sanding machines employed in wood working.

The objects of the invention are, first, to provide an all purpose sanding machine, in the sense that it is equipped with a double ended working head capable of vertical and rotative displacement and, by virtue of spindles on each end of the head, a belt may be used for vertical and horizontal sanding or, in place of the belt, abrasive surfaces may be applied to the spindles individually for vertical or horizontal sanding. Second, the provision of a sanding head having such flexibility that it may be conveniently and quickly moved to a variety of positions best suited to the type of work being performed, and third; the provision of a convertible sanding head capable of operating various forms of wood-working attachments.

Other objects of the invention include a removable work table for supporting various types of adjustable work fences; a removable platen resisting pressure of work on a belt sander when employed; a telescoping spring adjustment, combined with a tiltable spindle bearing for maintaining proper tension on the belt sander.

With the foregoing objects as paramount, the invention has further reference to certain features of accomplishment which will become apparent as the description proceeds, taken in connection with the accompanying drawings wherein:

Figure 1 is a front perspective view of a sanding machine constructed according to the invention, showing the sanding belt disposed horizontally.

Figure 2 is a similar view on slightly smaller scale, showing the work table applied and the sanding belt in vertical position.

Figure 3 is a fragmentary view of the machine cabinet in transverse section, showing the sanding head rotated to a position at right angles to the major axis of the cabinet and in vertical section.

Figure 3A is an end view of the motor pulley and spindle.

Figure 3B is a view thereof in longitudinal section.

Figure 4 is a plan view of the head elevating column casting.

Figure 5 is a plan view of the friction clamping collar for the head elevating column.

Figure 6 is a side elevational view thereof.

Figure 7 is a front perspective view of the sanding machine showing a brush sander attachment

2

operatively disposed on the idler spindle and an attendant working bridge.

Figure 8 is a plan view of the work table per se, and

Figure 9 is a detail plan view of the work table insert.

Continuing with a more detailed description of the drawing, reference numeral 10 denotes a cabinet which, for reasons to be presently defined, has a superimposed, removable top section 11, shown in Figure 2. The cabinet 10 has a false top 12 through the center of which extends a cylindrical head elevating column 13, operable vertically by means of the mechanism shown in detail in Figure 3.

In Figure 3, the cabinet 10 is shown in transverse section with the lower portion deleted. Within this cabinet is arranged an elevating column mounting 14, preferably a casting having an in-turned flange 15 at its top, defining a circular opening 16 through which the column 13 vertically reciprocates. Mounted upon the flange 15 and secured by bolts 17 is a clamp collar 18, shown in detail in Figures 5 and 6. This collar is split and the adjacent ends are equipped with ears 19, one of which is tapped and threaded. Through the aligned apertures in these ears is passed a threaded rod 20 (Fig. 3) which extends towards and through the front wall of the cabinet 10 and carries a crank 21, by which an operator in front of the cabinet may contract and expand the clamp collar 18 to respectively secure and release the elevating column 13 in adjusted positions of the work head, to be presently described.

The clamp collar 18 is further provided with radial lugs 22 on its outer surface, intermediate its top and lower flange 23 which underlie and support the false top 12 about the collar 18 where it protrudes through the top 12.

Spaced upwardly from the bottom of the mounting 14 is an integral plate 24, upon which rests the lower end of the column 13 when retracted. In the center of this plate, there is provided a boss 25, embracing an opening through which extends a screw rod 26, carrying acme threads 27. A bearing 28 surrounds a thrust bushing 29, the latter, in turn, being mounted or formed on the rod 26. The rod 26 passes through a cross-head 30 in the column 13 which is internally threaded to correspond with the threads of the rod 26.

The rod 26 carries on its lower end a gear 31, which meshes with a companion gear 32, mounted on the end of a shaft 33. The shaft 33 is jour-

naled in an elongated bearing 34 in the mounting 14 and extends through the front wall of the cabinet 10 and carries a wheel 35. A handle 36 is mounted near the periphery of the wheel 35 for convenience in rotating the same.

It is apparent from the foregoing that by rotating the wheel 35, the column 13 is raised or lowered through the medium of the screw rod 26 and when the desired elevation and orientation of the head is affected, the crank 21 is rotated to constrict the clamp collar 18 about the column 13.

Referring now specifically to the sanding head; it will be observed that tubular members 37 and 38, telescopically related, serve to carry a motor mounting 39 and an idler spindle bearing 40, respectively. In Figure 3, the motor, designated in other figures as 41, has been omitted to better disclose the mounting casting 39. The mounting is held in secure relation to the hollow shaft or tubular member 37 by means of a bolt 42 and is so shaped as to conform to one end of the motor 41. The opposite end of the member 37 is rotatably held in a split head 43, formed on the upper end of the elevating column 13 and which is provided with apertured ears 44 (Fig. 3) through which a bolt is passed to expand or contract the split head 43 to loosen or tighten the member 37 when it is desired to change the position of the motor 41 and the spindle 45.

The spindle 45, which may be hereinafter referred to from time to time as the driving spindle, is mounted on the armature shaft 46 of the motor 41 and is held thereon by a counter-sunk set screw 47. A sleeve 48 of rubber or other resilient material surrounds this spindle and is of slightly greater length than the spindle, as indicated in Figures 3 and 3B. A cap 49 is disposed over the end of the sleeve 48 and has a boss 50 which is conformably received in the end of the sleeve. A novel form of securing means for the cap 49 to prevent its displacement at high speed consists of a pair of screws 51 and 52 having interlocking heads 53 and 54 respectively. It will be noted especially in Figure 3B that the screw 52 is first screwed into place in the spindle and afterwards, the companion screw 51 is screwed into the cap 49 and its head 53 will be received in the correspondingly shaped recess 55 in the head 54 of the screw 52 (Fig. 3A). In this manner neither screw will become accidentally loosened to allow the cap 49 to be displaced at high speeds. Moreover, it is apparent that by differentially spacing the cap 49 in relation to the end of the spindle 45, variations in expansion of the resilient material of the sleeve 48 will occur to correspondingly alter the tension on a sanding belt mounted on the sleeve.

The sanding belt 56, when employed on the machine, as shown in Figures 1 and 2, embraces the driving spindle just described and an idler spindle consisting of a shaft 57 and a sleeve 58, also composed of a resilient material. The sleeve 58 is compressedly retained on the shaft 57 by a nut 59, threaded onto the end of the shaft 57, as shown in Figure 3. The belt 56 is not unlike conventional sanding belts in construction.

The smaller of the two telescoping tubular members 37 and 38 which carries the spindle bearing 40 is shaped at its outer end to define a sleeve 60 whose axis is transverse to that of the member 38 and is arcuately cut-away at 61 (Fig. 3). The bearing 40, which is loosely mounted in the sleeve 60 is adapted to pivot in this sleeve on an axis transverse to that of the sleeve 60, afforded by oppositely disposed bolts 62 entering

apertures in each side of the sleeve 60 and threaded into aligned openings in opposite sides of the bearing 40. In this manner, the bearing may be tilted in the sleeve 60 and in being so moved, the spindle 58 will be likewise displaced to cause the sanding belt to track on the spindles. A belt 63 (Fig. 7) drives the idler spindle from the driving spindle 45 by virtue of its engagement with the pulley 64 of the driving spindle and pulley 65 of the companion spindle. To control the angular displacement of the idler spindle as explained, a hand wheel 66 (Fig. 3) is provided, by which a screw 67 in the sleeve 60 is set against the lower portion of the bearing 40. Obviously, by advancing the screw 67, the sanding belt may be centered on the spindles while the latter are rotating.

The tubular member 38 has a longitudinally disposed key 68 (Fig. 3) held by screws 69, entering the key through the companion tubular member 37, to hold the members 37 and 38 against relative rotation but permitting longitudinal displacement. A compression spring 70 is disposed within the member 37 and bears against the inner end of the member 38, thrusting the latter outwardly to maintain tension on the sanding belt as well as on the driving belt 63.

A split collar 71 is mounted on the inner end of the tubular member 37 and has ears 72, apertured to receive a bolt 73 (Figs. 3 and 7), by which the collar is contracted on the member 37. A boss 74 is formed on the collar 71 and is provided with two internally threaded openings 75, the larger opening being adapted to receive the threaded stem of a star wheel 76 (Figs. 1 and 2) for the purpose of holding a platen board 77 (Fig. 1) and a platen cap 78 in position on the work head, the former as a backing for the belt sander 56. The smaller of the openings 75 receives a bolt for holding a belt guard, to be later identified. A companion star wheel 79 (Figs. 1 and 2) is mounted in the threaded opening 42 of the motor mounting 39 to secure the opposite end of the platen and cap.

It is well understood from the foregoing that the operating head of the sanding machine is capable of rotation, both on a vertical axis afforded by the column 13 and on a horizontal axis, by virtue of the head clamp 43 of the elevating column. Thus, the spindles 45 and 58 may be disposed to operate horizontally, as shown in Figure 1 or vertically, as shown in Figures 2, 3 and 7, either with or without the belt sander 56. When this element is dispensed with an abrasive sleeve (not shown) may be conformably slipped onto one or both of the spindles for individual use in sanding work where such limited abrasive surface will suffice.

In order to properly orient the spindles, that is, to dispose them in true horizontal or vertical planes, an arcuate segment *a'* (Figs. 3 and 7) is secured by means of bolt 69 to the midsection of tubular member 37 and complementary to this segment, a boss *b'* is formed on the head 43 which supports the elevating column 13. It is obvious that when the work head is rotated in the supporting head, the ends of the predeterminedly positioned segment *a'* will engage the boss *b'* at two extreme positions to determine the horizontal and vertical positions of the spindles.

The false top 12 of the cabinet is provided with an opening 80 at one end, adapted to accommodate the motor 41 when the latter is in lowered position as shown in Figure 7 and at the opposite

end, an opening 81 is provided to receive the bearing of the idler spindle 58.

To provide a support for work against the belt 56 in the position shown in Figure 2, the top section 11, earlier mentioned, is superimposed upon the cabinet 10 and upon this section, there is provided a flanged top or work table 82, shown in a detail plan view in Figure 8. This table has an elongated opening 83 therein which conforms to the spindles 48 and 58 and the belt 56 surrounding the same. It is apparent that an attachment, such as a work "fence" 84 (Fig. 2) may be adjustably mounted on the table 82 at desired angles to the surface of the sanding belt to facilitate sanding.

It is to be understood that the work table 11 is not merely an accessory but instead constitutes a part of the machine. It is disposed upon the base portion of the machine and requires no means of securing. The removability of the work table without complications leaves the working head in the proper working plane without necessity for raising or lowering the same as in some other machines and this feature accentuates the general flexibility of the present machine.

Should it be desired to dispense with the sanding belt 56 and employ only the spindles with abrasive sleeves, an insert 85 (Fig. 9), is placed in the opening 83 of the table, to rest upon the strips 86 in the sides of the opening. A locating strip 87 is disposed transversely on the insert 85 whose ends are receivable in notches 88 of the strips 86 to properly dispose the insert in relation to the spindles 48 and 58 and the ends 89 of the insert are cut to conform to these spindles.

In Figure 1 the sanding head is shown as a horizontal belt sander with the work table removed. A "work fence" 90 is adjustably mounted on the head to hold the work operative against the belt.

In Figure 7, the head is shown as rotated to a position to dispose the spindles vertically and on the idler spindle a brush sander 91 is mounted. This brush sander is of conventional construction and has a hollow core which receives the expandable sleeve of the spindle by which it is held operatively thereon. An auxiliary work table 92, supported upon a base 93 is cut away at 94 to conformably receive the brush sander 91. The base 93 is bolted to the false top 12 of the cabinet at 95. It will be observed also in Figure 7 that a guard 96 is provided for the belt 63 and is secured to the collar 71 and motor casting 39 by screws 97.

From the foregoing it is apparent that by virtue of the flexibility of the sanding head, a highly versatile machine is afforded.

Manifestly, the construction as shown and described is capable of some modification and such modification as may be construed to fall within the scope and meaning of the appended claims is also considered to be within the spirit and intent of the invention.

What is claimed is:

1. A sanding machine including a cabinet having a false top and a removable top section having a work table thereon, a work head supporting column vertically reciprocable in said cabinet, a work head carried by said column comprised of telescopically related tubular members rotatably mounted on said column, means for limiting rotative displacement of said head, work spindles mounted on the outer end of each of said tubular members whose axes are at right angles to that of said members, expandable sleeves carried by said spindles, sanding means on said

spindles, a motor supported by one of said tubular members to drive the spindle thereon, means for driving the companion spindle from said first spindle, means for tilting said companion spindle relative to said first spindle, means for raising and lowering said column, and means within one of said tubular members for exerting a constant pressure against the other to maintain tension on said driving means.

10 2. In a sanding machine, a cabinet, a work head supporting column movable vertically in said cabinet, a work head supported intermediate its ends on said column, said work head comprising telescopically related tubular members rotatably mounted on said column transverse to the axis thereof, a spindle mounted on the outer end of each of said members whose axes are substantially at right angles to the common axis of said members, and arranged to carry a sanding belt,

15 20 spring means wholly within one of said tubular members for axially expanding said tubular members to maintain constant tension on said belt, a motor suspended from one of said members for driving the spindle thereon, means for driving the companion spindle from said first spindle, means for tilting said companion spindle for tracking said sanding belt, means for raising and lowering said column and means for securing said column in adjusted positions.

25 25 3. In a sanding machine, a cabinet having a removable work table, a rotatable work head supporting column mounted for vertical movement in relation to said table, a longitudinally adjustable work head rotatably supported intermediate its ends upon and in transverse relation to said column, a spindle on one end of said head capable of tilting displacement, a second spindle on the opposite end of said head substantially parallel to said first spindle, a belt connecting said spindles, an expandable sleeve carried by each of said spindles, a motor for driving one of said spindles a threaded rod vertically disposed in said column and means for rotating said rod to vertically actuate said column.

30 35 40 45 4. A sanding machine including a cabinet a vertically movable work head supporting column in said cabinet, telescopically related tubular members constituting a working head rotatably supported intermediate its ends upon and in transverse relation to said supporting column, a compression spring in one of said tubular members effecting axial extension of said working head; a spindle on one end of said head, pivotally mounted for tilting displacement, a second spindle on the opposite end of said head and parallel with said first spindle to support an abrasive belt between said spindles, maintained in centered position on said spindles by the tiltability of said first spindle, an expandable sleeve on each of said spindles, a motor for operating said second spindle, means for driving said spindle from the second spindle, means for actuating said column and means for securing the latter in adjusted positions.

50 55 60 65 70 75 5. A sanding machine including a cabinet having a removable work table a work head supporting column movable vertically with respect to said table a longitudinally adjustable head comprised of telescopically related tubular members rotatably disposed on and in transverse relation to said column a coil spring enclosed in one of said tubular members for axially extending said head, a spindle at each end of said work head,

an abrasive belt interchangeably mounted on said spindles and held under tension of said spring, means for driving said spindles, a threaded rod in said column and means for rotating said rod to raise and lower said head.

6. A machine as described in claim 5, further defined in that one of the spindles is mounted in a bearing embraced by a sleeve secured to one end of said head at right angles to its longitudinal axis, wherein said bearing is suspended on diametrically opposed pivots for tilting displacement to effect tracking of a belt traveling thereon and means for adjusting the degree of displacement of said spindle.
